UNITED STATES PATENT OFFICE.

WILLIAM E. SHERWOOD, OF AUBURN, NEW YORK, ASSIGNOR TO THE EAGLE WAGON WORKS, OF AUBURN, NEW YORK, A CORPORATION OF NEW YORK.

SIDE-DUMP VEHICLE.

Application filed September 29, 1925. Serial No. 59,321.

This invention relates to dump cars of the tilting body side-delivery type adapted to be used for delivering coal and other materials which are capable of automatic discharge 5 through the outlet when the box is tilted in the direction of said outlet.

The main object is to provide a device of this character which may be easily and quickly applied to the chassis of various makes of 10 motor vehicles and other running gear without material, if any, alteration thereof.

Another object is to provide opposite lengthwise sides of the box or body with suitable discharge openings and closures there- 15 for capable of being manipulated by hand in controlling the discharge of the material from the box through the openings.

A further object is to provide simple and 20 efficient means for tilting the box laterally in reverse directions at such angles as will cause the automatic discharge of the material thru the openings when the corresponding closure is opened and to utilize the same means for locking the box in its tilted position.

Another object is to construct the box in 25 such manner that when tilted in the direction of either opening the material will be automatically concentrated toward and discharged through the opening when the cor- 30 responding closure is opened.

A further object is to provide the box with 35 removable partitions which when placed in operative position divide the interior of the box into compartments, each having a definite fractional capacity of the entire capacity of the box for carrying plural loads.

Other objects and uses relating to specific 40 parts of the device will be brought out in the following description:—

In the drawings:

Figure 1 is a perspective view of a dump car embodying the various features of the invention in which the dump box is adjusted to one of its tilting positions for discharging 45 a part of its load therefrom and also showing the partitions in operative position for dividing the interior of the box into several compartments.

Figure 2 is a transverse vertical sectional 50 view of the same device taken on line 2—2, Figure 1, except that the dump box is shown by full lines in its normal horizontal position

and both of the side doors closed, the dotted lines indicating the different positions to which the box or body may be tilted in dis- 55 charging the load at either side.

Figure 3 is a horizontal sectional view through one side of the box in the plane of line 3—3, Figure 2.

Figure 4 is a longitudinal vertical sec- 60 tional view taken on line 4—4, Figure 1.

Figure 5 is a detail vertical sectional view taken in the plane of line 5—5, Figure 4.

Figure 6 is a detail longitudinal vertical sectional view taken in the plane of line 6—6, 65 Figure 9.

Figure 7 is a detail horizontal sectional view partly broken away in the plane of line 7—7, Figure 4.

Figure 8 is a detail transverse vertical sec- 70 tional view taken in the plane of line 8—8, Figure 4.

Figure 9 is a horizontal sectional view taken in the plane of 9—9, Figure 4.

Figure 10 is a longitudinal vertical sec- 75 tional view taken in the plane of line 10—10, Figure 9, showing more particularly the gearing for transmitting motion from the main operating shaft to the crank shaft for tilting the box laterally in opposite directions.

This device is adapted to be mounted upon the frame A of any standard make or special form of chassis, preferably at the rear of the cab —a— of a motor vehicle or upon any trailer or its equivalent and comprises a main supporting frame —1—, a dump box —2— and suitable means for tilting the box laterally in opposite directions and holding it in its various positions of adjustment.

As illustrated more clearly in Figure 9, 90 the main frame comprises a pair of lengthwise sills or I-beams —3— arranged in transversely spaced parallel relation and in the same horizontal plane lengthwise of the axis and supported near their front ends upon a transversely extending cross bar or channel iron —4— which in turn is secured by clamping bolts —5— to the chassis frame A, said sills —3— being provided near their rear ends with V-shaped braces —6— clamped by bolts 95 —7— to the adjacent rear end of the chassis frame A as shown more clearly in Figure 4.

A pair of cross bars or angle irons —8— are bolted or otherwise secured to the upper

faces of the sills —3— near the front ends thereof and in longitudinally spaced relation lengthwise of said sills and preferably at right angles thereto so as to form a rigid part 5 of the main frame —1— and thereby to hold the rear end of the sills in fixed spaced relation.

A similar pair of cross bars or angle irons —8— are bolted or otherwise secured to the 10 upper faces of the sills —3— at right angles thereto and in longitudinally spaced relation and near the front ends thereof for additionally holding the sills in fixed relation and also to assist in forming a unitary supporting frame for the dump box and its operating mechanism as will be hereinafter more fully described.

The cross bars —8— and —8'— of both sets extend laterally beyond and preferably 20 equal distances from the outer faces of the sills and are, therefore, of substantially uniform length corresponding approximately to the width of the box —2— indicated by dotted lines in Figure 9, the cross bars of 25 each pair being arranged so that two of their flanges will face each other in an upright position or in parallel vertical planes to cooperate with similar pairs of cross bars —10— and —10'—, presently described, on 30 the underside of the box —2— for guiding said box in its vertical tilting movement and also for holding the box against lengthwise displacement relatively to the main supporting frame.

35 The outer ends of both pairs of cross bars —8— and —8'— are connected by longitudinally extending bolts —9— and —9'— respectively, the bolts of each set being parallel and preferably coaxial with those of 40 the other set and are arranged equal distances from the outer faces of the corresponding sills to form fulcrums about which the box —2— is adapted to be tilted in a manner hereinafter described.

45 The cross bars —10— and —10'— are secured to the underside or bottom of the box —2— through the medium of lengthwise angle irons —11— and —12—, the angle irons —11— being bolted or otherwise secured to 50 the upper faces of the cross bars —10— and —10'— in transversely spaced relation while the lengthwise bars —12— are bolted or otherwise secured to the underside or bottom of the box —2— in similar transversely spaced 55 relation and are also bolted or otherwise rigidly secured to the adjacent lengthwise bars —11— thereby establishing a rigid connection between the cross bars —10— and —10'— and bottom of the box —2—.

60 The cross bars —10— and —10'— of each pair are spaced apart lengthwise of the box to correspond to the spacing of the bars —8— and —8'— of each pair so as to move freely between their respective pairs of bars —8— 65 and —8'— with reasonably close contact

therewith for guiding the box in its tilting movement and holding it against longitudinal movement lengthwise of the frame.

These cross bars —10— and —10'— are 70 provided near their outer ends with slots —13— which are open at the bottom and closed at the top, said slots being disposed equal distances from the longitudinal center of the box corresponding to the distance 75 of the fulcrum bolts —9— and —9'— from said longitudinal center for receiving said bolts and establishing pivotal connection between them and the box to permit said box to be tilted about the axis of the bolts at 80 either side of the frame.

That is, when the box is in a normal horizontal position the closed upper ends of the slots form bearings resting upon the corresponding pivotal bolts —9— and permit the 85 box to be tilted upwardly and laterally in reverse directions about the axis of the bolts at either side, due to the fact that the slots are open at the bottom.

Box locking mechanism.

Suitable means is provided for locking the box in its normal horizontal position to the main frame —1— to hold it against lateral tilting movement or vertical vibration, particularly when the machine is in transit from one place to another in addition to the means previously described for guiding the box in its vertical movement and holding it against longitudinal movement relatively to the supporting frame and for this purpose is provided two longitudinally extending lock-bars —15— and —15'— located in close proximity to and along the outer edges of the sills —3—.

100 The bar —15— is provided with a pair of locking bolts —16— and —16'— at or near the ends thereof and guided in suitable apertures in the cross bars —8— and —8'— for supporting the bar in its operative position and permitting it to be moved forwardly and 105 rearwardly into and out of registering apertures in the rear cross bars —10— and —10'— respectively on the underside of the box or body —1— for locking the corresponding side of the box in its horizontal position.

110 The other bar —15'— is also provided with a pair of locking bolts —17— and —17'— which are guided in longitudinally aligned openings in the front bars —8— and —8'— respectively and serve to hold the bar —15— 115 in operative position and to permit its forward and rearward movement for moving the bolts —17— and —17'— into and out of registering opening in the front cross bars —10— and —10'— on the bottom of the box 120 for holding the corresponding side of said box in its horizontal position.

125 The rear ends of the lock bars —15— and —15'— are connected to opposite arms of an operating lever —18— which is pivoted 130

intermediate its ends at —19— to a bracket —20— on the rear cross bar —10— as shown more clearly in Figure 9. This lever extends transversely of the frame —1— just at the rear of the rear cross bar —10— and owing to the fact that the rear ends of the lock bars —15— and —15'— are connected to the lever at opposite sides of its pivot —19— it is evident that the movement 10 of the lever in one direction or the other will move the lock bars —15— and —15'— in reverse directions, said lever being provided at one end with a handle —21— by which it may be rocked about the axis of its pivot 15 —19—.

In Figure 9 the locking bolts and operating mechanism therefor are shown in their locking positions for holding the box in its normal horizontal plane but it is evident that 20 by rocking the handle end of the lever —18— from its normal position shown by full lines in Figure 9 to the position shown by dotted lines, the effect will be to withdraw the bolts —16— and —16'— and also —17— and 25 —17'— from engagement in their respective openings in the bars —10— and —10'— on the underside of the box thereby releasing said box to permit it to be tilted laterally in either direction upon their fulcrums —9— and —9'—, it being understood that when the 30 bolts are withdrawn from engagement with the bars —10— and —10'— they will still be held in the registering openings in the bars —8— and —8'—.

35 *Tilting mechanism.*

A pair of braces —22— are secured to and between the intermediate portions of the sills —8— in longitudinally spaced relation for 40 receiving and supporting between them a train of gears —23— and for partially supporting an operating shaft —24— and a crank shaft —25— as shown more clearly in Figures 2, 4, 9, and 10, the gear train —23— 45 serving as a means for transmitting rotary motion from the operating shaft to the crank shaft.

The operating shaft —24— extends lengthwise of the machine adjacent the inner side of 50 one of the sills —8— and is journaled near its rear end in a suitable bracket —26— on the rear end of the frame —1— as shown in Figures 1 and 9, the rear end of the shaft being easily accessible from the rear end of the 55 machine and is preferably provided with an angular portion —27— for the reception of a suitable hand-crank —28— whereby it may be rotated, the rear end of said shaft being journaled in suitable bearings in the braces 60 —22—, Figures 2 and 9.

The portion of the shaft —24— just at the 65 rear of the bracket —26— is provided with a toothed wheel —30— tight thereon and adapted to be engaged by a pawl or detent —31— which is pivoted to the bracket and

may be swung to either side of the gear for engaging the teeth thereof and holding the shaft against return movement when rotated in either direction in the act of tilting the box through the medium of mechanism presently described.

The crank shaft —25— is journaled in suitable bearings —32— on the undersides of the innermost cross bars —8— and —8'— to extend lengthwise of the frame —1— parallel 70 with the shaft —24— and substantially midway between the sills —3— and is also journaled intermediate its ends in suitable bearings in the braces —22—, Figure 4.

The opposite ends of the shaft are offset 80 radially to form crank arms —25'— which terminate in opposite axially extending bearings —25''—.

The bearings —25''— are positioned directly below the cross bars —10— and —10'— respectively and are connected thereto by 85 separate pairs of pitmen —33— each composed of telescoping sections —34— and —35—, the sections —34— of each pair being pivotally connected at one end to their corresponding bearings —25''— while the other sections —35— of each pair are pivotally connected at —36— to their corresponding cross bars —10— and —10'— on the underside of the box, the pitmen of each pair being normally disposed in upwardly diverging 90 planes from their respective bearings —25— as shown more clearly in Figure 2.

The pitman sections —35— are mainly tubular and sleeve upon their respective sections —34— thus permitting relative sliding 100 movement of the sections in tilting the box laterally in either direction.

The sockets in the sleeves —35— into which the sections —34— are inserted are closed at 105 the top while the upper ends of the sections —34— are of sufficient length to nearly engage the closed upper ends of the sockets when the box is in its normal horizontal position so that when the crank shaft —25— is turned about its axis in either direction the upper ends of the sections —34— at one side 110 will engage the closed upper ends of the sockets of their corresponding sections for tilting that side of the box upwardly while 115 the sections —34— and —35— at the opposite side will be free to slide one upon the other.

When the box is in its normal horizontal 120 position the crank arms —25'— will be disposed in a vertical plane with the bearings —25''— directly under the axis of the shaft —25— while the upper ends of the pitmen at each end of the shaft will be engaged with the underside of the cross bars —10— and —10'— on the underside of the box equal distances from and at opposite sides of said axis or between the axis and corresponding fulcrum bearings —9— and —9'—.

The gear train —23— for transmitting ro 125

tary motion from the operating shaft —24— to the crank shaft —25— is of the speed reducing or power multiplying type to enable the operator of the shaft —24— to easily tilt the box with the load therein for dumping purposes and also to restore the box to its normal horizontal position in a manner herein-after more fully explained.

The box —2— is provided in each of its 10 opposite lengthwise sides with one or more, in this instance two, discharge openings —40— those of each pair being preferably rectangular in cross section and juxtaposed edge to edge substantially midway between 15 the ends of the box so that when the box with the load therein is tilted toward either side the material therein will be discharged through the selected opening and into a portable chute —C— if desired, the end of the 20 chute adjacent the box being temporarily held in place by a chain —41— and hook —42— or equivalent holding means.

These openings —40— extend from the bottom of the box upwardly a sufficient distance 25 to permit the rapid discharge of the material from the box when the latter is tilted to the proper angle and are controlled by vertically movable gates —43—, one for each opening, each gate being guided in its vertical movement in grooved stiles —44— along the opposite upright edges thereof.

Each opening is also provided with a pair of laterally swinging chute gates —45— and a drop gate —46—, the gates —45— being 35 hinged to the opposite vertical stiles of their corresponding opening —40— to extend the full height thereof and adapted to close against the outer face of the adjacent slide gate —43— and to open outwardly at substantially right angles thereto to concentrate the discharging coal toward the center of the chute.

The drop gate —46— is hinged to the lower 45 wall of the opening or bottom of the box to extend the full length thereof and is adapted to close against the outer faces of the closed gates —45— and to open downwardly and outwardly to an inclined plane for additionally directing the discharged material into 50 the chute.

In other words, the swinging gates —45— and —46— for each discharge opening constitute supplemental closures therefor when closed and also serve as a guide chute for the 55 material when discharging thru said opening, it being understood that the portable chute —C— may be removed and carried on the load when the vehicle is in transit from one place to another.

60 The dump box may be of any size or capacity but when used for carrying coal is preferably made of two ton capacity, but may be divided into one ton compartments by a transverse partition —48— which is removably supported at its opposite upright edges

in suitable guides —49— in the opposite lengthwise sides of the box substantially midway between its ends while one of the one ton compartments as, for example, the front half of the box may be again divided 70 into one-half ton compartments by a lengthwise partition —50— having its opposite upright edges slidably mounted in suitable upright guides —51— in the front end wall of the box and on the partition —48— midway 75 between the sides of said box as shown more clearly in Figure 1 and also in Figure 4.

The upright guides for the lengthwise partition —50— are shown in detail in Figure 7 80 while Figure 1 shows the bottom of the same partition with flanges —48'— thereon adapted to rest upon the bottom of the box.

The guides —51— on the front end of the box and transverse partition —48— for receiving the central lengthwise partition 85 —50— are similar to the guides —49— shown in Figure 1 while the lower edge of this lengthwise partition is provided with flanges —50'— similar to the flanges —48'— to rest upon the bottom of the box.

These bottom flanges or feet —48'— and —50'— on the lower edges of the partitions —48— and —50— also serve to reinforce or stiffen said partitions, the upper edges of both partitions being also reinforced by angle 95 irons —48''— and —50''—.

The opposite ends of the reinforcing flanges —48''— on the upper edge of the partition —48— are preferably extended over the upper edges of the adjacent sides of the box to be bolted thereto by clamping bolts —52— to hold said partition against vertical movement if desired, but mainly to assist in holding the sides of the box against spreading under lateral pressure of the load if it 105 should be found to be necessary.

The rear end of the box —2— is also provided with a central discharge opening to be used for rear end discharge when necessary but is normally closed by a drop lid or gate 110 —54— having its lower edge hinged by trunnions —55— to the bottom of the box, Figure 5, to swing rearwardly and downwardly and the upper portions of its opposite upright edges provided with T-shaped lugs —56— 115 adapted to enter slotted brackets —57— on the adjacent portions of the box, lock pins —58— being removably inserted in apertures in the brackets —57— in the rear of the lugs —56— as shown in Figures 4 and 5 to hold 120 the rear end gate in its closed position.

The opposite sides of the box adjacent the discharge openings —40— converge outwardly or laterally in the direction of discharge and in like manner the side walls of the box converge rearwardly in the direction of the rear end discharge opening.

The object of these outward converging walls is to cause the material to automatically concentrate toward the discharge open- 125 130

ing when dumping the load and thereby to avoid the necessity of shoveling the material from the corners toward the openings.

This construction is particularly advantageous in side-delivery dump boxes in that the tilting of the box in either direction will cause the converging sides of the box or compartments to act as an inclined chute in which the sides as well as the bottom of the box or compartment will be inclined downwardly toward the discharge opening thereby assuring a complete discharge of the material through said opening when the box is tilted to the required angle.

Any suitable means may be provided for opening the gates —43— one at a time and for this purpose each gate is provided with a separate operating lever —60—, those at each side of the box being pivoted at —61— to the upper intervening portion of the corresponding side of the box to swing about the same axis, said levers extending in opposite directions lengthwise of the box to opposite sides of their respective gates to which they are connected by links —62—, Figure 1, the free ends of the levers being provided with suitable handles —60'— by which they may be rocked vertically for opening and closing their respective gates —43—.

When the gates are closed by the downward rocking movement of their respective levers the latter will be engaged in suitable keepers —64— on the adjacent sides of the box for holding the closed gates against outward swinging movement by pressure of the load within the box.

The upper edge of each gate —43— is also provided with a keeper —65— adapted to engage the outer face of the upper edge of the corresponding drop lid —46— when the corresponding gates —45— and lid —46— are closed thereby assuring the retention of those parts in their closed position as long as the gate —43— is closed.

Suitable means is provided for preventing the application of the hand crank —28— to the rear end —27— of the shaft —24— until the lever —21— has been operated to unlock the locking bars —15— and —15'— and for this purpose is provided a guard lever —70— extending forwardly and rearwardly directly under the portion of the lever —21— between its pivot —19— and its connection with the locking bar as shown in Figure 9 and having its front end pivoted at —71— to the rear cross bar —8— of the main supporting frame and its rear end provided with a lateral offset —72— movable to and from a position across the rear end —27— of the shaft —24— when the hand crank —28— is removed.

The intermediate portion of the guard lever —70— is provided with a cam slot —73— directly under the adjacent portion 65 of the lever —21— which latter is provided

with a pin —74— normally projecting into the cam slot —73—, said cam slot being inclined laterally and rearwardly from the stud or pin —74— toward the handle end —21— of the lever —18—.

The guard lever —70— is held in its operative position with its offset end —72— across the rear end of the shaft —24— by means of a spring —75—, Figure 9, so that the end wall of the cam slot —73— will be yieldingly held against the pin —74—.

The lever —18— is also held in its normal locking position by means of a spring —76—, Figure 6.

The cam slot —73— is also provided with a rearward offset extension —73'—, the open side of the slot being closed by a plate —77— to prevent displacement of the pin —74— from the cam slot —73—.

Referring again to the box —2— it is preferably made octagonal with the openings —40— of both pairs in the central portions of opposite lengthwise sides and the remaining portions of said sides at the front and rear of the openings diverging or inclined inwardly, the central portions of the lengthwise sides of the box in which are the openings —40— being parallel.

The opposite ends of the box are also parallel and, therefore, all of the angles at the junctions of the eight sides of the box are obtuse to facilitate the discharge of the material from either side of the box when tilted in that direction.

Operation.

Assuming that the loaded box is locked in its horizontal position against tilting movement as shown in Figures 2, 4 and 9 and that it is desired to discharge the load from one side or the other of the box by tilting the same laterally in the required direction as for example as shown in Figure 1, then, the first operation is to rock the lever —21— rearwardly from the position shown by full lines in Figure 9 to the position shown by dotted lines for withdrawing the locking rods —15— and —15'— from their locking positions during which operation the pin —74— will be drawn against the rear wall of the cam slot —73— with a sliding engagement therewith for forcing the guard lever from the position shown by full lines in Figure 9 to the position shown by dotted lines therein thereby withdrawing the offset portion —72— out of registration with the rear end —27— of the shaft —24— to permit the application of the hand crank —28— to the extension —27—.

As soon as the guard lever —70— has been tripped in the manner just described, the pin —74— will have entered the offset —73'— of the cam slot —73— thereby locking the lever —21— in its locked releasing position and also holding the guard lever in its tripping position.

When the hand crank —28— has been applied to the extension —27— it is rotated in the proper direction to transmit similar rotary movement to the shaft —24— which, through the medium of the gear train —23—, will rotate the crank shaft —25— in the desired direction.

This rotation of the crank shaft —25— will cause its crank arms —25'— to move in the same direction thereby forcing the pitman sections —33— at the corresponding side of the axis of the crank shaft —25— upwardly against the closed ends of the sockets in the adjacent sleeves —35— and causing a similar upward movement of the sleeve sections and consequent upward tilting movement of the corresponding side of the box upon the fulcrums —9— and —9'— in the opposite side of the box, it being understood that the upwardly tilting side of the box will move from the corresponding bearings —9— and —9'—.

During this movement of the crank arms —25'— in one direction for tilting the corresponding side of the box upwardly the sections —33— extending toward the lower side of the box will be partially withdrawn from their sleeve sections —35— and this movement is continued until the crank arms —25'— and lifting pitmen —33— assume a practically straight line.

That is, the crank arms —25'— and extensible pitmen —33— constitute toggles by which the box is raised and lowered upon one or the other of its fulcrums —9— and —9'— according to the direction of rotation of the crank shaft —25— and these pitmen are constructed so that when those of either side are used for lifting the corresponding side of the box to its maximum elevation or until the toggles are straightened the pitmen at the opposite side are gradually being extended during a part of that movement and will then begin to shorten, reaching the minimum shortening movement at about the time the first-named toggle assumes a straightened position whereby the second-named pitmen will act as a stop for preventing the return movement of the box when the operating shaft —24— is locked by means of the ratchet —30— and pawl —31—, it being understood that the pawl —31— is reversible to engage the teeth of the ratchet wheel —30— at either side of its axis to hold the shaft and part operated thereby in its box tilting position.

By releasing the pawl —31—, the shaft —24— and parts operated thereby may be returned to their normal positions and the box re-locked by a slight lateral movement of the guard member lever —70— which will release the pin —74— from engagement in the offset slot —73'— and permit the lock operating lever —21— to return to its locking position, it being understood that prior

to this last operation the hand crank will have been removed to permit the return of the guard lever —70— to its position across the extension —27—.

In like manner, the operation of the shaft —24— and parts actuated thereby may be reversed for causing the discharge of the load from the other side of the box than that previously described.

Although I have shown and described a specific construction of side dump car and the various features for carrying out the object of the invention, it is evident that the various elements entering into that construction may be considerably modified and, therefore, I do not wish to limit myself to this construction.

I claim:

1. In a vehicle of the character described, a tiltable body, a rotary shaft having a crank arm, means for rotating the shaft, and extensible pitmen having one end connected to the crank arm and their other ends connected to the body at opposite sides of the axis of the shaft whereby when the shaft is rotated in one direction the corresponding pitmen will elevate the adjacent portion of the body and cause an extension of the other pitman.

2. In a vehicle of the character described, a frame, a shaft journaled on the intermediate portion of the frame and provided with a crank arm, a dump body having spaced fulcrum bearings on the frame at opposite sides of the shaft, means for rotating the shaft, extensible pitmen connected at one end to the crank arm and having their other ends connected to the body at opposite sides of the shaft whereby the rotation of the shaft in one direction will cause one of the pitmen to tilt the body about one of its fulcrums and cause an extension of the other pitman.

3. A vehicle as in claim 2 in which each pitman is composed of sections slidably one upon the other.

4. A vehicle as in claim 2 in which the fulcrums for the tilting body are disposed substantially equal distances from the axis of the shaft.

5. A vehicle as in claim 2 in which the crank arm of the shaft is disposed in a substantially vertical position midway between the fulcrums when the body is resting on both fulcrums.

6. In a vehicle of the character described, a frame, a shaft journaled on the frame, and provided with longitudinally spaced crank arms extending in the same direction from the axis thereof, a dump body having fulcrum bearings upon the frame equal distances from and at opposite sides of the shaft to enable the body to tilt in opposite directions about either fulcrum, means for rotating the shaft, and separate pitmen each having one end connected to one of the crank arms and its other end connected to the body between the

shaft and one of the fulcrums and composed of sections slidable one upon the other.

7. A vehicle as in claim 2 in which the frame and body are provided with co-operative means for holding the body and frame against relative movement lengthwise of the shaft.

8. In a vehicle of the character described, a frame having fulcrums in spaced relation equal distances from and at opposite sides of the longitudinal center of the frame, a shaft journaled on the frame midway between the fulcra and provided with longitudinally spaced crank arms, a dump body fulcrumed on said bearings to tilt in opposite directions about either fulcrum, a pair of pitmen having one end connected to one of the crank arms and their opposite ends pivotally connected to the body at opposite sides of the crank shaft, an additional pair of pitmen having one end connected to the other crank arm and their opposite ends pivotally connected to the body at opposite sides of the crank shaft, each pitman being composed of sections slidable one upon the other, and means for rotating the crank shaft in reverse directions.

9. In a side delivery dump box, a supporting frame having fulcrum bearings on oppo-

site lengthwise sides thereof, a dump body tiltable laterally about either of said bearings, and means for effecting said tilting movement, said means including a crank shaft and pitman connections between the crank shaft and body, said pitman connections each composed of sections slidable one upon the other and means for rotating the crank shaft.

10. In a vehicle of the character described, a frame having fulcrum bearings in spaced relation equal distances from and at opposite sides of the longitudinal center of the frame, a dump body fulcrumed on said bearings to tilt in opposite directions about either fulcrum, means for tilting said body about either fulcrum including a rotary shaft having means for receiving a hand crank by which it may be rotated, means for locking and releasing the body in and from its normal position of rest upon both fulcrums, and means controlled by the locking means for preventing the placement of the hand crank upon the shaft when the locking means is in its locking position.

In witness whereof I have hereunto set my hand this 18th day of September 1925.

WILLIAM E. SHERWOOD.
